UNITED STATES PATENT OFFICE.

JOHN BUCKMASTER, OF ALTON, ILLINOIS.

SHOW-CASE.

SPECIFICATION forming part of Letters Patent No. 409,009, dated August 13, 1889.

Application filed March 19, 1889. Serial No. 303,835. (No model.)

To all whom it may concern:

Be it known that I, JOHN BUCKMASTER, of Alton, in the county of Madison and State of Illinois, have invented a certain new and 5 useful Improvement in Show-Cases, of which the following is a full, clear, and exact description, reference being had to the accompanying drawings, forming part of this specification.

10 This invention relates to a spring-opening show-case especially adapted for the exhibit of cigars, jewelry, &c., that require to be protected from dust, dampness, or injury by any other means from exposure when not on exhibit, and yet quickly opened up for the inspection of customers; and the invention consists in features of novelty hereinafter fully described, and pointed out in the claim.

Figure I is a top view of the show-case, 20 showing the lids closed. Fig. II is a like view showing the lids elevated. Fig. III is an enlarged vertical end section taken on line III III, Fig. II, and shows the position of the springs after the elevation of the lids. Fig. IV is an enlarged vertical end section 25 taken on line IV IV, Fig. I, and shows the position of the springs when the lids are closed; and Fig. V is an enlarged vertical detail section taken on line V V, Fig. I, and 30 shows the position of the spring-catch and push-pin when the lids are locked in their closed position.

Referring to the drawings, 1 represents the bottom, 2 the sides, and 3 the ends, of the case. 35 4 is the cross-partition that divides the operative spring-chamber 5 from the exhibit-chamber, and 6 is the cover of said spring-chamber.

7 represents the sectional folding lids, which 40 are preferably of equal diameter, the inner edges of which meet together when closed over the middle of the case, the joint between them being surmounted by the bead 8, that is secured to the lid that is last to close and over-45 laps the meeting edge of the other. The lids are respectively secured by hinges 9 to the side boards of the case, and are limited in the extent of their opening by the straps 10, which may be made out of any suitable material 50 that is both strong enough for the purpose and sufficiently tractable not to interfere with the folding and unfolding of the lids.

I will now describe the toggle-spring device by which I effect the automatic elevation of the lids when it is desired to exhibit the 55 contents of the case.

11 represents two contracting spiral springs whose lower hooks 12 are secured by staples or eyelet-screws 13 to the bottom of the case, inside the operative spring-chamber 5. The 60 surmounting hooks 14 of said spiral springs engage through the perforations 15 with the inner ends of the fulcrum-levers 16, which levers are hung on the fulcrum pins or bolts 17, that are secured in the partition-piece 4 65 and project inwardly into the spring-chamber. Wide washers 18 between said levers and the heads of the fulcrum-pins keep the levers from diverging from their correct vertical movement. The outer ends of the fulcrum-levers 16 are seated within the bifurcated forks 19 at the lower ends of the toggle-links 20, to which the lever is connected by the pivot pins or bolts 21. The upper ends of said toggle-links occupy pivotal seats between the perforated lugs 22 of the brackets 23, to which the said toggle-links are connected by the pivot pins or bolts 24. The 70 said brackets are secured to the under side of the lids 7 by the screws 25.

26 represents a spring snap-catch that is located inside the spring-chamber 5, the lower end of the strap of which spring-catch is secured to the end piece of the case inside the spring-chamber by screws or nails 27, and the 75 upper end of the strap is surmounted by the head of the catch 28.

29 is a push-pin, which is secured to the strap of the spring snap-catch and projects through a perforation 30 in the said end piece 90 of the case sufficiently, so that when pushed inward flush with the outside of the case it releases the spring-catch, which catch works freely in said spring-chamber and in the cut-away 31 in the cover of said chamber and 95 the cut-away 32 in the under side of the lid 7, that surmounts it.

A catch-plate 33, which is provided with an elongated slot 34, within which the spring-catch works, is secured by screws to the under side of said lid around the cut-away 32. The front edge of said plate projects under the front side of the cut-away 32 to the same extent as said cut-away projects over the top 100

of the end piece 3. This projection of the edge of said plate, it will be seen, forms a catch-hold 35, on which the head of the catch latches when the lids are closed in the position shown in Figs. I, IV, and V. The lid which is provided with the stop-bead is latched by said catch, and said stop-bead holds down the adjacent lid.

Now, when it is desired to open the case for exhibit, all that is necessary to do is to operate the push-pin 29, which unlatches the catch, and the lids are instantly automatically thrown up by the action of the springs, the fulcrum-levers, and toggle-links into the position shown in Figs. II and III. To effect said opening when the lids are unlatched by pushing in the pin 29, that governs the spring-catch, the spiral springs 11 contract to their normal condition and draw downward the inner ends of the fulcrum-levers 16, which consequently throw up their outer ends, and by the toggle-links that connect said ends of the fulcrum-levers with the lids the said lids are elevated.

The device is a convenience to both the salesmen and the inspector of the goods under exhibit, and is an advantageous set-off to a counter display in jewelry, cigar, and other stores where the goods require to be protected from injury by dust, dampness, &c.,

when not on exhibit, and yet to be easily thrown open to exhibit at any time required and allow many such cases to be speedily handled.

The partition 4, that incloses the spring-chamber, may, if desired, be a looking-glass, 35 which is placed so as to reflect into the exhibit-receptacle of the case, and which thus enhances the beauty of the exhibit.

The cases may be made of any material desired, and their lids made, as shown, with 40 wooden frames inclosing glass panels or of any other suitable construction.

I claim as my invention—

In a show-case, the combination of the case with its folding lids, the spring-chamber 5, the 45 spring snap-catch 26, the push-pin that operates said catch, the spiral springs 11, the fulcrum-levers 16, the pins on which said levers fulcrum, the toggle-links 20, the means of connection of said spiral springs to the bottom of the case and to the fulcrum-levers, the pivot-pins that connect said fulcrum-levers to the toggle-links, the brackets 23, and pivot-pins 24, that secure the toggle-links to the folding lids, substantially as described, and 55 for the purpose set forth.

JOHN BUCKMASTER.

In presence of—

WM. L. PATES,
JASON C. BRAMHALL.
